UNITED STATES PATENT OFFICE.

FRANK H. KAISER, OF BUFFALO, NEW YORK.

REFILLABLE FUSE-PLUG.

1,062,240.

Specification of Letters Patent. Patented May 20, 1913.

Application filed October 3, 1911, Serial No. 652,556. Renewed January 10, 1913. Serial No. 741,348.

To all whom it may concern:

Be it known that I, FRANK H. KAISER, citizen of the United States, residing at Buffalo, in the county of Erie and State of New York, have invented certain new and useful Improvements in Refillable Fuse-Plugs, of which the following is a specification.

The primary object of my invention is 10 the provision of a very simple, cheap and efficient refillable fuse plug.

A further object is to provide a plug of this character in which the ends of the fuse wire are held in place by the caps.

15 A further object is to provide a plug of this character in which the ends of the fuse wire are held in place between the caps forming the terminal ends of the plug and circular heads or washers interposed between the fiber insulating shell and the said caps.

Still another object is to provide a refractory sheathing inclosing the fuse wire and acting to smother the arc when the fuse 25 blows.

My invention is illustrated in the accompanying drawing, in which:—

Figure 1 is a perspective view of a fuse plug constructed in accordance with my invention; Fig. 2 is a longitudinal diametrical section; and Fig. 3 is a perspective view of one of the caps and its accompanying washer and screw, separated.

Corresponding and like parts are referred 35 to in the following description and indicated in all the views of the accompanying drawing by the same reference characters.

Referring to the drawing, 2 designates the 40 usual cylindrical shell of hard fiber or other insulating material, this shell being open at its opposite ends. Mounted upon the ends of the shell and detachable therefrom are the caps 3. These caps are made of thin brass and are each provided with a depressed central portion 4 and a marginal flange or rim 5 which fits snugly around the adjacent end of the fuse plug. Through the center of the depressed portion 4 of the cap passes a screw 6.

50 Interposed between the ends of the shell 2 and the caps 3 are circular heads or washers 7. These, as will be seen from Fig. 3 of the drawing, are each circular in form and provided with an upstanding marginal flange 8. The center of each washer or 55 head 7 is slightly thickened and interiorly

screw threaded for the passage of the screw 6. Each of the washers 7 is provided with a perforation 9 for the passage of the adjacent terminal end of the fuse wire 10. 60 The fuse wire of course extends entirely through the shell 2 and its ends are passed through the perforations 9 and then angularly bent so as to lie against the outer faces of the washers or heads 7. The intermediate portion of the fuse wire is surrounded by an asbestos sheathing 11.

In assembling the fuse as above described, the caps are removed from the shell 2 and the fuse wire placed within the shell, surrounded of course by the sheathing 11. The ends of the fuse wire are passed through the perforations 9 and angularly bent down upon the heads or washers 7, as shown in Fig. 2, the washers resting loosely upon the 75 ends of the fiber shell. The caps 3 are then put in place and slipped over the ends of the fiber shell. The screws 6 are then inserted and screwed home, thereby drawing the caps and washers or heads 7 toward 80 each other and of course drawing the caps home, the caps being thus retained in position not only by their engagement with the fiber shell, but also by the engagement of the screws 6 with the heads or washers 7 85 which in turn are held in place by reason of the angularly bent ends of the fuse wire. The depressed central portion of each cap will engage the adjacent angularly bent end of the fuse wire and the fuse wire will be 90 clamped between the head or washer 7 and the cap, and the cap will thus have a thoroughly good electrical engagement with the fuse wire. It will be noted that when the screw 6 is screwed home the head of the 95 screw is entirely housed within the depressed portion 4 of the cap so that it does not project beyond the capped end of the fuse plug.

It will be obvious that the fuse may be 100 readily removed by removing the screws 6 and thus permitting the easy detachment of the fuse wire from the washers 7, and that the fuse wire may be readily replaced when burned out. Furthermore it will be seen 105 that the arc caused by the blowing out of the fuse will be smothered by the asbestos sheathing 11.

It will of course be noted that the central 110 depressed portion 4 is less in exterior diameter than the interior diameter of the annular flange 8 of the washer 7, so that when

the screw is turned the depressed portion 5 may fit down into the flange 8 and thus securely clamp the adjacent end of the fuse wire. It will be seen that I have provided therefor an insulating shell having at each 10 end clamping members between which the fuse wire engages and that I have provided means, namely, the screw 6, whereby these clamping members may be moved toward each other and into clamping engagement 15 with the fuse wire.

The fuse wire is coiled around the screw 6 and not only is the fuse wire clamped between the brass washer 8 and the cap 3, but 15 by reason of the fact that the cap has an annular groove into which an annular flange on the washer fits, dust and dirt are prevented from working in through the cap and between the cap and washer might possibly 20 prevent a good electrical contact between the cap and the fuse wire.

While I have shown what I believe to be the best form of my invention, I do not wish to be limited to these specific details, as it is 25 obvious that many changes might be made without departing from the spirit of the invention.

Having thus described the invention, what is claimed as new is:

30 1. A fuse plug including a hollow insulating shell, a fuse wire supported within the shell and having angularly bent ends,

clamping members mounted upon the ends of the shell between which the angularly bent ends of the fuse wire are received, said 35 clamping members comprising disk-like washers, and caps, each cap having a marginal flange embracing the adjacent end of the shell, said clamping members being formed, one with an annular recess and the 40 other with an annular flange adapted to be received in said recess whereby to provide a dust-proof engagement between the clamping members.

2. A fuse plug comprising an insulating 45 shell, disk like washers supported one at each end of the shell and having perforations through which the ends of the fuse wire pass, said washers each having a marginal flange extending outward from the 50 shell, caps at each end of the shell, each cap having a marginal flange embracing the adjacent end of the shell, and a depressed central portion, and screws for forcing said caps toward the said washers and into 55 clamping engagement with the ends of the fuse wire.

In testimony whereof I affix my signature in presence of two witnesses.

FRANK H. KAISER. [L.S.]
